UNITED STATES PATENT OFFICE.

BENJAMIN F. LANTERMAN, OF CHICAGO, ILLINOIS.

CUTTER-HEAD.

SPECIFICATION forming part of Letters Patent No. 286,450, dated October 9, 1883.

Application filed March 29, 1882. (No model.)

To all whom it may concern:

Be it known that I, BENJAMIN F. LANTERMAN, a citizen of the United States, residing at Chicago, in the county of Cook and State 5 of Illinois, have invented a new and useful Improvement in Wood-Planing Machines, of which the following is a specification.

My invention relates to the cutters of wood-planing machines, in which a revolving head 10 or holder carrying the knives operates in conjunction with machinery moving the material to be planed; and the object of the improvement is to overcome the necessity of grinding away unnecessary material in the process of 15 sharpening the knife.

The invention consists in the employment of an extremely thin knife and an improved means of holding it to the cutter-head, as shown in the accompanying drawings, in 20 which—

Figure 1 represents an end view of the cutter-head, and Fig. 2 a sectional plan of the same.

In carrying out my invention I use the 25 ordinary revolving prismatic head, A, secured to a shaft, with which it rotates. This head is usually made square, as shown, to the faces of which I secure the cutting-knife C, which consists of a thin strip of tempered steel having 30 a beveled sharpened edge projecting over the face of the cutter-head. The knife differs from an ordinary planer-knife in having no holes or slots for bolts, but is secured by the pressure of the clamp B b acting on the knife 35 at a point immediately back of its projecting sharpened edge, and placed forward of the bolts.

The clamp, as shown at B b, consists of a 40 tempered steel bar of the length of the knife, but considerably wider, having holes through which bolts d are inserted for the purpose of holding it to the cutter and cutter-head, and a beveled forward edge, b, which, when in place, forms a continuation of the beveled edge 45 of the knife. The clamp is made to press firmly on the knife immediately back of the edge of the cutter-head and close to the cutting-edge of the knife by means of the single set of screw-bolts d, and to insure this result 50 the under side of the clamp is removed from contact with either the knife or head, except

at its outer edges, the forward edge resting near the knife-edge and the rear portion on the back portion of the revolving head. This may be effected by hollowing the under side 55 of the clamp or raising the rear of the cutter-head, as at shoulder D; or a combination of both methods may be employed, as desired. It will be evident that with this mode of constructing the clamp the pressure of the bolts 60 is made to act at the point where it is most effective, and constitutes a re-enforce to the knife, making it as stiff as if the clamp and knife were one piece, instead of being distributed over the greater part of the knife's 65 surface, and particularly the rear portion, which is the result when the clamp and head are not in this manner adjusted. Thus the necessity for bolt-holes in the knife is dispensed with and the use of an extremely thin knife 70 rendered possible, which can be readily filed to the proper degree of sharpness without the necessity of removal and grinding away a useless amount of material, which is the common method at the present time. 75

I am aware that clamps have been heretofore employed to hold the knife in its place on planer-heads; but, so far as I am aware, none of them have clamped the knife along its back, immediately behind the cutting-edge, 80 directly upon the cutter-head with a single set of bolts.

I claim as my invention—

1. The prismatic solid cutter-head A, combined with the clamp-plate B, concavo-convex 85 in cross-section, and the single series of clamping-screws d, arranged along the median line of said clamp-plate, and the thin cutter-blade C, whereby said clamp-plate bears only at its two edges and the thin cutter-blade is secured 90 by means of a single set of screws, as set forth.

2. The prismatic solid cutter-head A, provided with the shoulder D, combined with the thin cutter-blade C, and the clamp-plate B, resting at its back edge upon and against said 95 shoulder, and the single series of clamp-bolts, d, substantially as shown.

BENJAMIN F. LANTERMAN.
